UNITED STATES PATENT OFFICE.

CHARLES LESLIE NEWLAND, OF ELTHAM, ENGLAND.

MACHINE-TOOL HOLDER.

1,406,064.

Specification of Letters Patent.

Patented Feb. 7, 1922.

Application filed April 15, 1920. Serial No. 374,168.

To all whom it may concern:

Be it known that I, CHARLES LESLIE NEWLAND, a subject of His Majesty the King of England, and resident of Eltham, in the county of Kent, Kingdom of England, have invented certain new and useful Improvements in or Relating to Machine-Tool Holders (for which I have filed an application in Great Britain dated Apr. 3, 1919, No. 8434,) of which the following is a specification.

This invention relates to turret tool holders of the kind in which the tools are peripherally arranged in a holder adapted to be rotated so as to bring the several tools into operation when desired, the holder being clamped in a split ring and the tools being maintained in the operative position by a spring-pressed pawl. The present invention has for its object to provide an improved construction of tool holder of the aforesaid type.

According to the present invention a multiple tool holder of the aforesaid type is adapted to carry a set of tools projecting from the face thereof, the said tools being intended but not limited to use for interior work. The tool holder is preferably formed with an integral ratchet adapted to co-operate with an adjustable pawl directly engaging the ratchet wheel at one end and subjected to the action of a spring at the other end so as to prevent rotation of the ratchet wheel and tool holder unless in the desired direction. The holes to receive the facially-disposed tools extend the entire width of the tool holder and ratchet wheel. The tools are interchangeable and interchangeable means are provided to lock the tools in the operative position. An opening is provided axially of the tool holder and extends through the entire width thereof and the ratchet wheel.

I will describe with reference to the accompanying drawing a construction in accordance with the present invention but I do not limit myself to the precise details of construction described and illustrated.

Figure 1 is a side elevation of a machine-tool-holder in accordance with the present invention, part thereof being shown in section.

Figure 2 is a plan of Figure 1 showing the tool-holder as used for outside and inside work.

Figure 3 is a cross section on the line A.A Figure 2.

Figure 4 is a section on the line B.B. Figure 1 looking in the direction of the arrows.

Fig. 5 is a detail side view of a portion 60 of the device seen in Fig. 2.

Referring to the drawing the bar 1 hereinbefore referred to is formed with or has permanently or removably attached thereto a split ring 2 capable of being contracted 65 by a screwed pin 3 or equivalent so as to grip or bind on a rearwardly projecting portion 4 of the rotatable member 5 and hold the same locked in the desired position. The rotatable tool carrying member is preferably provided with a reduced part 4 which is hereinafter referred to as the rear part and is engaged by the split ring 2. The outer or forward portion 6 of the rotatable member 5 is provided with a plurality of 70 radially arranged holes 7 into each of which a tool can be pushed one of which is shown at 8 and retained therein by locking pins 9 disposed concentrically of the axis of the rotatable member and being preferably 75 manipulated into and out of locking position from the rear face of the reduced portion of the rotatable member.

Concentrically arranged relatively to the axis of the rotatable member and extending through or for any desired distance into the said member are a plurality of holes 10, slots or grooves each capable of carrying any desired tool such as shown at 11, which can be locked in position by set screws 12 80 85 radially arranged with respect to the rotatable member 5 and capable of being screwed into locking position against the respective tool.

The rear end 4 of the reduced portion of 90 the rotatable member is provided with a plurality of teeth 13 corresponding in number to the number of tools which can be carried by the rotatable member 5. Co-operating with the aforesaid teeth which may be in the form of shallow ratchet teeth is a spring 95 pressed pawl 14 mounted preferably in a recess 15 in the carrying bar 1 and adapted by a screw 16 or equivalent to be adjusted or raised or lowered relatively to a central position so as to vary the operative position of the rotatable member 5. The rotatable member carrying the tools is free to rotate in the direction of the arrow C Figure 1 but is locked against rotational movement in the 100 105 110

direction of the arrow D Figure 1 because of engagement of the spring pressed pawl 14 with one or other of the ratchet teeth. The 5 spring pressed pawl and ratchet wheel provide a ready means for adjustment of the height of the tool relatively to the centre of the work which adjustment is easily and quickly effected. Lateral displacement of the rotatable member may be avoided by providing the reduced portion with a peripheral groove 17 or recess and a set pin 18 adapted to be screwed through the split ring 2 into engagement with the said peripheral groove or recess 17.

15 The central portion of the rotatable member may be hollow to receive a bar having a screwed end disposed eccentrically of the bar and adapted to receive a chuck as shown in Figure 4, wherein 19 is the bar above referred to and 20 a chuck of known type having split jaws to receive a tool shank.

20 The tool-holder may be used in the horizontal position as shown in Figure 5 in which position the tool is turned through an 25 angle of ninety degrees relatively to the position shown in Figure 2. In Figure 5 the relative position of the tool and the work are shown.

25 The rotatable member may be arranged and adapted to carry four or other suitable 30 number of peripherally arranged tools or exterior cutters, and four or other suitable number of facially arranged tool or interior 35 cutters and the tools are preferably of the circular form with or without a flat side or sides on each tool to facilitate locking and for adjustment. In the preferred form of 40 tool the latter is preferably of two different diameters, the holding part being of larger diameter than the tool part proper and the 45 tools are interchangeable so that any tool will fit any of the tool holes in the rotatable member. The interior tools may be formed with an inward or outward set at the cutting end.

45 The main length of the carrying bar may be circular, rectangular, square, or polygonal in cross section.

50 The heads of the various locking pins as also the head of the split clamping pin are squared and are all of the same size so that

one box key or manipulating key fits all the heads of the locking pins and the clamping pin.

What I claim is:—

55 1. A multiple tool holder for metal working machines comprising an arm having a split bearing, a tool carrier rotatably mounted in the said bearing, a ratchet wheel rigidly connected with the said tool holder and disposed concentrically therewith, a plurality of facial tools mounted in holes disposed parallel to the axis of the tool carrier and concentrically arranged therewith, means to clamp the said tool carrier and ratchet wheel in operative position, and means to adjust the ratchet wheel circularly so as to adjust the height of the tool relatively to the work.

70 2. A multiple tool holder for metal working machines comprising an arm having a split bearing at one end, a hollow cylindrical casing having radially arranged holes therethrough and a reduced portion formed as a ratchet wheel adapted to be rotatably 75 clamped in position in the split bearing, a plurality of holes in the hollow cylindrical casing disposed parallel to the axis of the said casing and concentric therewith, means adapted to prevent circular displacement of 80 the ratchet wheel and tool carrier and also to allow of adjustment of the tool carrier, and means to prevent longitudinal displacement of the tool carrier.

85 3. A multiple tool holder comprising an arm having a split bearing at one end, a tool carrier rotatably mounted therein, a ratchet wheel formed integral with the tool carrier, an axial bore through the tool carrier and ratchet wheel, tool-receiving radial holes 90 spaced round the tool carrier, longitudinally disposed tool receiving holes through the tool carrier and ratchet wheel and concentric with the axis thereof, a spring-pressed pawl located in a recess in the tool carrier 95 arm, means to adjust the said pawl, and means to retain the tool carrier and ratchet wheel in the split bearing when unclamped therein.

100 In testimony whereof I have hereunto signed my name.

CHARLES LESLIE NEWLAND.
